UNITED STATES PATENT OFFICE.

ARTHUR S. BALDWIN, OF BALTIMORE, MARYLAND.

SAFETY PERCUSSION-FUSE.

1,311,672.

Specification of Letters Patent. Patented July 29, 1919.

Application filed January 8, 1917. Serial No. 141,098.

To all whom it may concern:

Be it known that I, ARTHUR S. BALDWIN, a citizen of the United States, residing at Baltimore, in the State of Maryland, have 5 invented certain new and useful Improvements in Safety Percussion-Fuses, of which the following is a specification.

This invention relates to improvements in fuses for shells or projectiles and has reference to that class of fuses known as 10 inertia operated fuses.

The present invention is directed particularly to improved means for retaining the firing devices of the fuse in a safety condition, both against accidental arming, and 15 against firing, even if said devices should accidentally be moved to the armed position.

In carrying out my invention I make use of a firing pin and plunger, which are normally capable of independent movement 20 when in the safety, unarmed condition, but which become locked together when armed, and I also provide improved means for holding the locked-together plunger and 25 pin, against movement toward the primer until the fuse is projected with a shell from a gun.

The invention is illustrated in the accompanying drawing wherein,—

30 Figure 1, illustrates the improved fuse device in longitudinal section,—the parts being shown in the safety or unarmed position.

Fig. 2, shows a cross-sectional detail 35 through the same,—the section being taken on the line 2—2 of Fig. 1.

Fig. 3, illustrates the fuse in longitudinal section but with the firing devices in an armed but locked position to prevent firing.

40 Fig. 4, shows a cross-sectional detail through the latter,—the section being taken on the line 4—4 of Fig. 3, and

Fig. 5, illustrates the detached plunger in side elevation.

45 In the drawing the case or stock 6, has a form adapting it for use in the base of a shell or projectile. This however, is immaterial as it is obvious, the device, with slight modification, can readily be adapted for attachment to the point or nose of a shell.

50 The case or stock is provided with exterior screw-threads 7, and an interior circular chamber 8, which latter extends longitudinally of the stock, and is closed at the inner 55 end by a cap 9, in which the primer 10, and an additional powder charge 11, are located.

A plunger 12, is positioned in the chamber 8, of the stock, and in the present instance, this plunger has the form of a metal body of a cross-sectional shape that conforms to 60 the shape of the chamber in which it is located.

The plunger body, in the present instance, has a passage 13, extending upwardly from the lower end and a central passage 14, that 65 extends downwardly from the upper end but of a smaller diameter than the passage 13, whereby to form an annular shoulder 15, at the point where the two passages communicate.

A firing pin 16, extends longitudinally in the passages 13, and 14, and one end of this pin has a head 17, whose upper end forms an annular shoulder 18, in the passage 13, so that a coiled spring 19, may encircle the pin 70 and have one end seated on the head-shoulder 18, and the other end seated against the shoulder 15, in the central passage. The lower end of the pin-head 18, is tapered or pointed whereby to produce an undercut or 75 shoulder 20, for a purpose which will presently be explained.

At the lower end, the plunger body 12, has an annular projection or boss 21, which depends around the head of the firing pin 80 and projects toward the outer end wall 22, of the stock chamber.

By referring to Fig. 1, of the drawing it will be seen that the coiled spring 19, acts to force the plunger body in one direction 90 and the firing pin in a reverse direction and by its action the plunger is yieldingly pressed toward the cap 9, at one end of the chamber 8, while the beveled end of the firing pin head is held yieldingly against the 95 end wall 22, at the opposite end of the chamber 8.

From actual tests I have found that under severe accidental shocks, much less however, than the shock produced upon firing 100 from a gun, the spring 19, may yield sufficiently to allow the plunger to move longitudinally in the chamber 8, and strike against the end wall 22, with sufficient force to lock the plunger and firing-pin head together, which would cause the firing devices 105 to become armed, and I therefore provide improved means to avoid this dangerous condition, which will now be explained.

The plunger body 12, is provided with a 110 longitudinal passage 23, which is eccentrically located therein, and which extends

from the outer end into the plunger body. I also provide the plunger body with a cross-wise or horizontal slot 24, which extends across the said passage 23, so that a thin plate 25, may extend across said passage like a partition. It will be noted that the plate 25, is carried entirely by the plunger body and has no connection with the wall of the chamber 8, or with the stock.

- 10 A punch bar or stem 26, has one end rigidly secured in the end of the case or stock and said bar enters the end of the passage 23, in the plunger body. The inner end of this bar or stem terminates in the passage 15 adjacent to the partition plate 25, when the plunger body is in the safety, or unarmed position, as shown in Fig. 1, of the drawing. This bar 26, and the passage 25, form a die-like structure, in that the bar must punch 20 through the plate 25, to permit longitudinal movement of the plunger, as will presently be more fully explained.

The inner end 27, of the plunger body is provided with a cross-wise notch which 25 forms a ledge 28, in a plane below said end and produces a vertical wall 29, between the ledge and the end, and a vertical passage or slot 30, is provided in the side of said body, which passage extends from the lower end 30 of the body up to and opens at said ledge 28. A yielding or spring bar 31, has its lower end seated in the end of the case or stock and said bar extends freely through the passage or slot 30, in the plunger body and projects above the ledge 28. This projecting end of the spring bar carries a laterally-extending head or lug 32, which projects toward the center of the plunger body for a purpose which will presently be explained.

- 40 In practice the case or stock containing the fuse device is attached to a shell in the well-known way, at which time the plunger body 12, is held by the spring 19, with its inner end 27, seated against the cap 9, and 45 with the firing pin pressed in a reverse direction with its beveled head-end seated against the end wall 22, of the chamber 8. At this time the inner end of the punch 26, will have position in the passage 23, adjacent to the partition plate 25, so that movement of the plunger body toward the end 22, of chamber 8, cannot take place unless the force is sufficient to cause the punch to pass through or pierce the partition plate. 50 I have found by tests that a thin copper plate meets the requirements of this partition and will withstand the punching tendency of the punch 26, under any ordinary shock to which the shell might be subjected during handling or shipment.

The punch or stem 26, by entering the vertical passage 23, in the plunger body also serves as a guide to prevent rotation of the plunger-body in the stock or case.

- 60 65 While the plunger-body is in the unarmed

or safety position, the upper end of the spring bar 31, and the head or lug 32, thereon, will be pressed outwardly,—the head or lug at such time seating against the vertical wall 29, and projecting over the ledge 28, of the plunger-body.

If for any reason a shell containing this improved fuse device should accidentally receive sufficient shock to cause the punch to pierce the plate 25, and drive the plunger-body against the end wall 22, with sufficient force to upset the metal of the projection or boss and lock the body and firing pin together, then upon such movement of the plunger body from the cap 9, the spring bar 31, will spring inwardly and project the lug or head 32, over the end 27, of the plunger body and securely hold the plunger body and firing pin against a return movement toward the primer 10, and thereby lock the armed firing devices, plunger and pin, against movement in a direction that would cause an accidental explosion.

It will thus be seen that the punch pin 26, and partition plate 25, will serve to prevent the plunger body and firing pin from becoming locked together under ordinary shocks, but that if sufficient shock is given to cause said parts to become armed, then the spring bar 31, and head 32, will operate to prevent the armed devices from moving toward the primer, and the shell will still be safe to handle.

When the shell is fired, however, from a gun, the centrifugal motion imparted to it during its flight will cause the spring bar 31 and head 32, to swing outwardly, and the plunger body will thus be released so that when the shell strikes the plunger body and firing pin may move forward while the pin strikes the primer 10, and causes the desired explosion.

Having described my invention what I claim and desire to secure by United States Letters Patent is,—

1. In a safety fuse device for shells or projectiles the combination with a case having a chamber therein, of an explosive element; firing devices in said chamber; means for restraining the said firing devices against movement to an armed position and locking means for engaging the firing devices when they move to the armed position and prevent movement of the same to the explosive element.

2. In a safety fuse device for shells or projectiles the combination with a case having a chamber therein, of an explosive element; firing devices in said chamber; means for restraining the said firing devices against movement to an armed position and centrifugally-movable means for engaging the firing devices when they move to the armed position.

3. In a safety fuse device for shells or

projectiles the combination with a case having a chamber therein, or an explosive element; firing devices in said chamber; means for restraining the said firing devices 5 against movement to an armed position and yielding means movable between the firing devices and explosive element when said firing devices move to the armed position and said yielding means being movable by centrifugal force to release the firing devices.

4. In a safety fuse device for shells or projectiles the combination with a case having a chamber therein, of an explosive element; firing devices in said chamber including a plunger; means for restraining the plunger against movement in a direction to arm the firing devices and means for locking the plunger against movement toward the explosive element after said firing devices have been moved to the armed position.

5. In a safety fuse device for shells or projectiles the combination with a case having a chamber therein, of an explosive element; firing devices in said chamber including a plunger; means for restraining said plunger against movement to an armed position and yielding means normally held by the plunger in an inoperative position and released when the plunger moves to an 25 armed position said yielding means when released engaging the plunger to prevent movement of the latter to the firing element.

6. In a safety fuse device for shells or projectiles the combination with a case having a chamber therein, of an explosive element; a plunger body in said chamber; a firing pin in said chamber; means for preventing movement of the firing pin toward the explosive element; means for restraining 30 said plunger against movement from the safety position, and means for locking the plunger and pin against movement toward the explosive element when they become armed.

45 7. In a safety fuse device for shells or projectiles the combination with a case having a chamber therein, of an explosive element; firing devices in said chamber including a plunger; a plate carried by the plunger; means carried by the case for engaging said plate to restrain the plunger against movement and means for locking the plunger and firing devices against movement toward the explosive element after the restraining means has released the plunger.

8. In a safety fuse device for shells or projectiles the combination with a case having a chamber therein, of an explosive element; firing devices in said chamber including a plunger; a plate carried by the plunger; a pin carried by the case, and engaging the plate to restrain the plunger against movement, and a yielding device normally

held inactive by the plunger and movable to engage said plunger when the latter is released by the restraining pin and plate. 65

9. In a safety fuse device for shells or projectiles the combination with a case having a chamber therein, of an explosive element; a plunger in said chamber said plunger having a passage therein, a partition in the plunger-passage; a pin carried by the case and entering said passage with its end at one side of said partition; a firing pin also in said chamber, and means for locking 70 the plunger and firing pin after they have been moved to an armed position.

10. In a safety fuse device for shells or projectiles the combination with a case having a chamber therein, of an explosive element; a plunger in said chamber said plunger having a passage therein; a partition in the plunger-passage; a pin carried by the case and entering said passage with its end at one side of said partition; a firing pin 80 with which the plunger becomes engaged under shock, and a yielding engaging device to engage the plunger when the latter and the firing pin become engaged, to prevent movement of the plunger and pin toward 85 the explosive element.

11. In a safety fuse device for shells or projectiles the combination with a case having a chamber therein, of an explosive element; a plunger in said chamber said plunger having a central passage and also a side passage; a firing pin in the central passage of the plunger; means for locking the plunger and firing pin together by shock and a yielding arm extending through the side 95 passage of the plunger and yieldingly engaging the plunger when the latter and the firing pin become locked together, to prevent accidental movement of plunger and pin toward the firing element. 100

105 12. In a safety fuse device for shells or projectiles the combination with a case having a chamber therein, of an explosive element; a plunger body in said chamber; a firing pin extending longitudinally in the 110 plunger body; means for normally holding the firing pin against movement toward the explosive element; means independent of the pin-holding means to normally prevent movement of the plunger body with respect 115 to the firing pin, and means for holding both the firing pin and plunger body against movement toward the explosive element when the plunger and pin become accidentally armed. 120

In testimony whereof I affix my signature in the presence of two witnesses.
